UNITED STATES PATENT OFFICE.

ARTHUR W. WALKER, OF MALDEN, MASSACHUSETTS.

DESIGN FOR A GRATE-BAR.

SPECIFICATION forming part of Design No. 28,361, dated March 8, 1898.

Application filed January 17, 1898. Serial No. 666,998. Term of patent 14 years.

To all whom it may concern:

Be it known that I, ARTHUR W. WALKER, a citizen of the United States, residing at Malden, in the county of Middlesex and Commonwealth of Massachusetts, have invented and produced a new and original Design for a Grate-Bar, of which the following is a specification.

In the drawings accompanying and forming a part of this specification, Figure 1 is a perspective view of a grate-bar illustrating my design; and Fig. 2 is a cross-sectional view thereof on the line xx , Fig. 1.

The leading feature of my design for a grate-bar consists in a bar-like base or body portion having symmetrically-located oppositely-convexed projections along its opposite sides extending above and below the top and bottom, respectively, of the base and merging thereinto by concaved portions from their apices.

The bar-like base or body of the grate-bar is shown as composed of parallel longitudinal members a , connected by lateral separated

cross-bars b , forming an apertured base. 25 Along the sides of the base are arranged symmetrically-located projections c , having convexed outer faces c' , substantially lozenge-shaped, the apices $c^2 c^3$ of said projections extending above and below the top and bottom, respectively, of the base, while the cross-bars b are continued in outwardly-curved portions $b^2 b^3$ to said apices, sweeping in easy curves from the plane of the top and bottom of the body to the apices of the projections. 35

Having fully described my novel design, what I claim, and desire to secure by Letters Patent, is—

The design for a grate-bar, substantially as herein shown and described. 40

In testimony whereof I have signed my name to this specification in the presence of two subscribing witnesses.

ARTHUR W. WALKER.
